UNITED STATES PATENT OFFICE.

HARRY VISSERING, OF CHICAGO, ILLINOIS.

INDICATOR FOR RADIATORS.

No. 904,163.

Specification of Letters Patent.

Patented Nov. 17, 1908.

Application filed April 29, 1907. Serial No. 370,951.

To all whom it may concern:

Be it known that I, HARRY VISSERING, a citizen of the United States, residing at Chicago, in the county of Cook and State of Illinois, have invented certain new and useful Improvements in Indicators for Radiators, of which the following is a specification.

My invention relates to gages or indicators for showing the condition of the water in the radiators commonly employed for cooling the water circulated about the cylinders of explosive engines, as employed in motor vehicles. The invention has for its objects; to provide a gage or indicator of greater reliability than the gages heretofore employed; to provide a gage which will not freeze, and finally, to provide a gage which can be utilized as a filling tube. One embodiment of the invention is illustrated in the accompanying drawings, wherein,

Figure 1 is a longitudinal section through the hood of an automobile, and shows the relation of my improved indicator and the radiator to the engine and other parts of the mechanism used therewith,

Figure 2 is a vertical section through the radiator showing the indicator or gage in side elevation,

Figure 3 is a sectional front view showing the top of the radiator with the indicator mounted thereon, and

Figure 4 is an enlarged longitudinal section through the indicator.

Heretofore gages for indicating the height of water in cooling radiators have been placed along the side thereof in the same manner as the water gages employed on an ordinary boiler. This old form of gage has been found unreliable and unsatisfactory for the reason that the gage is often frozen up in cold weather, is liable to become plugged up by dirt thus preventing the gage from indicating the true height of the water in the radiators, and steam is often pocketed in the gage causing the level of the water to be incorrectly indicated. My invention is designed to overcome these objections and this is accomplished by placing the gage or indicator at a point where it is exposed to water of the highest temperature in the radiator so that it will not freeze, and in using a tube which has no crooks or bends to collect dirt. The indicator also acts on a different principle from the former type of gage in that it is further adapted to indi-

cate the height of water in the radiator by means of vapor or bubbles raised by the high temperature. Briefly stated, the gage comprises an upright tube provided with a window and mounted on the top of the radiator. The tube is provided at its top with a removable cap whereby it may be utilized for replenishing the water in the radiator when desired.

Referring first to Figure 1 of the drawing, 1 is the cooling radiator mounted at the front of the hood 2, 3 is my improved indicator carried upon the top of the radiator 1, 4 are the cylinders of the explosive engine, which are to be cooled by water from the radiator 1, 5 is the ordinary centrifugal pump for circulating the water continuously through the radiator and cylinder casings, 6 is the outlet pipe from the bottom of the radiator to the pump 5, 7 is the pipe leading from the pump 5 to the cylinder casings, and 8 are the return pipes to the top of the radiator. The radiator is of the ordinary type as indicated in Figures 2 and 3, and consists of the upper and lower headers connected by a series of small pipes provided with cooling fins. The indicator 3 is shown in cross section in Figure 4, and comprises a tube portion 9 screw threaded at its lower end to the collar 10, and carrying at its upper end the cap 11. The side of the tube 9 is cut away as shown, to expose the glass 12, which glass 12 consists of a tube fitting tightly inside the tube 9 and provided with the gaskets 13 and 14. The cap 11 is provided at its top with a small vent 15 for relieving any pressure which may accumulate in the radiator due to the high temperature of the water.

When the radiator is first filled and the water extends up inside the indicator 3, the height thereof can be seen through the gage glass 12, but the gage is further useful in that it indicates when the water has reached such a low level as to give rise to a dangerous condition, which condition is indicated by the formation of vapor or bubbles of steam, which vapor or bubbles rise inside of the gage glass and may be observed by the operator. It will be seen therefore, that whenever the water in the radiator reaches a dangerously low level this fact is indicated with certainty in the gage. It will also be apparent that as the tube is a straight one and is placed at the extreme top of the radiator, there is no danger of steam pocketing.

forming, or of the indicator freezing or becoming clogged in any way. It will also be seen that this form of gage obviates the necessity of a separate filling passage, as the water in the radiator may be replenished by simply removing the cap 11, and filling the radiator through the tube. As the gage is intended also to indicate the condition of the water by means of vapor or bubbles as well as by means of the water line, as shown in the glass, a very short gage tube may be used, thus rendering the device very cheap as compared with the ordinary gage glasses, which must be extended along a considerable distance at the side of the radiator.

Having thus described my invention and illustrated its use, what I claim as new and desire to secure by Letters Patent is the following.

- 20 1. The combination with a water cooling radiator, of an indicator mounted thereon and comprising an upright tube communicating at its lower end with the top of the radiator and provided at its side with a window and having a removable cap where-
- 25 dow.
2. The combination with a water cooling radiator, of an indicator mounted thereon

and comprising an upright tube communicating at its lower end with the top of the radiator and provided at the side with a window and having a removable cap where-
30 by the tube may constitute a filling passage.

3. The combination with a water cooling radiator, of an indicator mounted thereon and comprising an upright tube communicating at its lower end with the top of the radiator and provided at the side with a window and having a removable cap pro-
35 vided with a small vent.

4. The combination with a water cooling radiator, of an indicator seated on the top thereof, and comprising a short upright tube provided with a window and adapted to indicate the condition of the water in the radiator by the formation of bubbles in the said tube.

In testimony whereof I have hereunto signed my name in the presence of the two subscribed witnesses.

HARRY VISSERING.
